GEORGE HARSIN AND T. M. KIRKPATRICK, OF KIRKVILLE, IOWA.

Letters Patent No. 74,851, dated February 11, 1863.

IMPROVEMENT IN HAND-LOOM.

The Schedule referred to in these Letters Patent and making part of the same.

TO ALL WHOM IT MAY CONCERN:

Be it known that we, GEORGE HARSIN and T. M. KIRKPATRICK, of Kirkville, in the county of Wapello, and State of Iowa, have invented certain new and useful Improvements in Hand-Looms; and we do hereby declare that the following is a full, clear, and exact description of the same, reference being had to the annexed drawings, making part of this specification, in which—

Figure 1 is a perspective view.

Figure 2 is a vertical section.

Figure 3 is a top view of the front part of the loom; and

Figure 4 is a vertical section of parts of the mechanism.

The same letters are employed in the designation of the same parts.

Our improvements relate to that class of looms in which the power is applied by hand, and their nature will appear from the following description and claims.

A is the batten or lathe, by the oscillation of which the mechanism is actuated. It is connected by the rod B with the swinging arm C, pivoted to the frame of the loom. This oscillates with the batten, and gives a reciprocating motion to the hooked rods D and E. The rod E has a notch in the bottom intended to push against bars across the double wheel G', giving a quarter revolution to the wheel with each motion of the lathe towards the operator. The treadles F, pivoted to the frame at one end, rest on cams G on the axle of the wheel G'. The cams are placed at right angles to one another, as shown in fig. 4, and with each movement of the lathe towards the operator. The treadles F are alternately raised by the cams. The treadles, on the descent of the cams, are depressed by springs F'. H are the harness-frames, attached by eyes in their ends to rigid guide-rods, attached to the frame in a vertical position. The harness-frames are attached to the treadles by rods H'. I is the yarn-roller, which has a pulley on the end, around which a cord, I', is carried, one end of which is attached to the frame, and the other to a lever, I'', by drawing on which the cord can be tightened or loosened. The rack I'' holds the lever in place. By means of the lever the operator can regulate the tension applied to the yarn-roller.

The cloth-roller is actuated by a take-up, as follows: A pinion, K¹, on the cloth-roller K, gears into another on the shaft of the ratchet-wheel K². This ratchet-wheel is caused to revolve with the motion of the lathe, as the cloth is woven by the feed-hand K³ attached to the lever K⁴, which is moved backwards and forwards by the connecting-rod K⁵, fastened to the crank-arm K⁶. A reciprocating motion is given to the crank-arm K⁶ by a spring, K⁷, attached to the axle of the crank, and resting on pins projecting from the face of the double wheel G'. As this wheel revolves, the spring will be raised, pushing forward the feed-band, and moving the cloth-roller. When the pin passes from under the spring, the latter flies back, thus retracting the feed-hand; the motion being so regulated by the position of the pins, that the cloth shall be wound up at the proper time in relation to the movement of the shuttle.

The shuttle is thrown by the following means: The wheel L attached to the shaft L', has pins projecting from its face, to engage the hook upon the arm D, which is actuated by the oscillating-arm C, the rods D and E operating their respective parts of the mechanism alternately. Arm, M, is attached to the shaft L', having friction-wheels on their extremities, which, with the revolution of the shaft, bear successively on the arm N, which are constructed with faces inclined in the direction of the revolution of the arm M. These arms project from counter-shafts N', turning on journals resting on the frame. The picker-staff O are fastened to these counter-shafts, and when the arm N is pressed down by the arm M striking against it, the picker-staff will be thrown smartly forward, throwing the shuttle attached thereto by cords. The picker-staff are drawn instantly back to their original vertical position by the spring P, connected with the counter-shafts by cords P'.

The shuttle-boxes A' are connected with the lathe by hinges, which will permit them to be folded down when not in use, and are supported in a horizontal position by hooks attached to the lathe when the loom is in operation.

What we claim as our invention, and desire to secure by Letters Patent, is—

1. The combination and arrangement of the harness-frames H, attached to guide-rods H', the treadles F, cams G, wheel G', notched bar E, oscillating-arm C, rod B, and lathe A, substantially as described.

2. The take-up mechanism, consisting of the wheel G', and parts K⁷, K⁶, K⁵, K⁴, K³, and K², arranged substantially as described.

3. The combination of the reciprocating bar D, wheel L, shaft L', arms M and N, and picker-staff O, substantially as described.

4. The arrangement of the yarn-roller I, having a pulley on its end, and the cord I¹, one end being fastened to the frame, and the other to the lever I², adjustably held in position by the rack I³, for the purpose of regulating the tension of the yarn-roller, substantially as described. In testimony whereof, we have signed our names to this specification in the presence of two subscribing witnesses.

GEORGE HARSIN,
T. M. KIRKPATRICK.
